UNITED STATES PATENT OFFICE.

CARMI O. BENTON, OF GRAINFIELD, KANSAS.

RAILROAD-TIE.

No. 910,452.

Specification of Letters Patent.

Patented Jan. 19, 1909.

Application filed June 11, 1908. Serial No. 437,886.

To all whom it may concern:

Be it known that I, CARMY O. BENTON, a citizen of the United States, residing at Grainfield, in the county of Gove, State of Kansas; have invented certain new and useful Improvements in Railroad-Ties; and I do hereby declare the following to be a full, clear, and exact description of the invention, such as will enable others skilled in the art to which it appertains to make and use the same.

This invention relates to railway ties, and has for one of its objects to improve the construction and increase the efficiency and utility of devices of this character.

Another object of the invention is to produce a railway tie in sections centrally united, and with the sections movable to a limited extent laterally, to provide for the automatic adjustment of the ties at the curved portions of the road bed.

Another object of the invention is to produce a tie comprising a central immovable member and end sections engaging the central member and movable laterally to a limited extent.

With these and other objects in view the invention consists in certain novel features of construction as hereafter shown and described and then specifically pointed out in the claims, and in the drawings illustrating the preferred embodiment of the invention, Figure 1 is a plan view. Fig. 2 is a side elevation partly in section. Fig. 3 is a bottom plan view. Fig. 4 is a transverse section on the line 4—4 of Fig. 1.

The improved device is formed in two rail supporting sections 10—11 engaging end to end, and with a tubular member or sleeve 12, the latter secured by the bolts 13 or suitable fastening means to the tie sections. The sections 10—11 do not fit the central section closely, at the sides as shown in Fig. 4 so that a limited amount of movement is permitted laterally, whereby the rail supporting sections are free to automatically adjust themselves under the strains imparted to the rails at curves and thus prevent the unequal binding of the members. The tie section 10 being secured in the casing 12 by a single bolt 13 and the tie section 11 being likewise secured in the casing by a single bolt 13, swing slightly laterally upon these bolts, as will be obvious. The lower face of the tubular member is formed with ribs 14 preferably crossing at right angles and spaced apart to

define a plurality of pockets or cavities 15, into which the tamping material enters and thus firmly "beds" the central member in the road bed, and effectually prevents the "creeping" of the ties both longitudinally and transversely of the road bed. The ribs also materially strengthen the tubular member.

The rails represented at 16 are supported upon the tie sections 10—11, by clamp plates 17, secured to the tie sections by bolts 18, or other suitable means. The outer clamp plates are relatively wide, and bear against the outer surface of the rail, while the inner clamp plates are relatively narrow and bear against the correspondingly narrow portion of the rail, so that as the tie sections play back and forth to the limited extent noted within the central tubular member, the relatively narrow inner clamp plates permit this slight lateral movement without producing cramping effect between the rails and tie sections.

The central tubular member is of metal and may be cast of iron or steel, and the tie sections 10—11 are also preferably of metal, and of any required shape, but may also be of wood if preferred.

What is claimed, is:

1. A railway tie comprising a central tubular member adapted to be immovably embedded in the road bed, and two tie sections engaging end to end within said tubular member and movable laterally therein to a limited extent.

2. A railway tie comprising a central tubular member adapted to be immovably embedded in the road bed, two tie sections engaging end to end within said tubular member and movable laterally therein to a limited extent, and means for securing said tie sections from movement longitudinally of the tubular member.

3. A railway tie comprising a central tubular member having ribs spaced apart and crossing at right angles upon the lower face and adapted to be immovably embedded in the road bed, and two tie sections engaging end to end within said tubular member and movable laterally therein to a limited extent.

4. A railway tie comprising a central tubular member adapted to be immovably embedded in the road bed, two tie sections engaging end to end within said tubular member and movable laterally therein to a limited extent.

extent, and means for clamping the rails to said tie sections.

5. A railway tie comprising a central tubular member adapted to be immovably embedded in the road bed, two tie sections engaging end to end within said tubular member and movable laterally therein to a limited extent, means for securing said tie sections from movement longitudinally of the tubular member, and means for clamping the rails to said tie sections.

10 6. A railway tie comprising a central tubular member adapted to be immovably embedded in the road bed, two tie sections en-

gaging end to end within said tubular member and movable laterally therein to a limited extent, relatively wide rail braces secured to the tie sections and adapted to bear against the outer faces of the rails, and relatively narrow rail braces secured to the tie sections and adapted to bear against the inner faces of the rails.

In testimony whereof, I affix my signature, in presence of two witnesses.

CARMI O. BENTON.
